UNITED STATES PATENT OFFICE.

EDWARD AUSTIN WATSON, OF ANDERSON, SOUTH CAROLINA, ASSIGNOR OF ONE-HALF
TO ROLLY J. FLOYD, OF GREENVILLE, SOUTH CAROLINA.

SPINNING MACHINE.

Application filed June 21, 1921. Serial No. 479,340.

To all whom it may concern:

Be it known that I, EDWARD AUSTIN WATSON, a citizen of the United States, residing at Anderson, in the county of Anderson and 5 State of South Carolina, have invented certain new and useful Improvements in Spinning Machines, of which the following is a specification.

The present invention relates to controlling mechanism for spinning machines, and more particularly to means whereby a small amount is wound at one end of the bobbin prior to the full length winding operation. It is of the general type disclosed in my 15 prior Patent 1,350,903, issued August 24, 1920.

The object of the present invention is to provide relatively simple mechanism of a novel character that can be applied to a 20 well-known type of apparatus, and will effectively secure the desired sequence of operations.

In the accompanying drawings:—

Figure 1 is a view in elevation of the usual 25 builder cam and builder arm, together with the short-stroke mechanism constituting the invention,

Figure 2 is a perspective view of the mechanism,

Figure 3 is a front elevation of the same, and

Figures 4 and 5 are detail views showing the roller in active and in inactive relations to the short-stroke cam.

In the embodiment disclosed the usual 35 swinging builder arm is shown at 6 and is adapted to be operated in the usual manner by the main builder cam 7. Secured to this builder cam 7 is a short-stroke cam 8. A 40 bracket 9, adjustably mounted on the builder cam 6 by a bolt 10, which passes through a slot 11 in said bracket, constitutes a mounting for a transversely sliding bar 11^a. Journaled on the end of this bar is a roller 12 45 that is movable into cooperative engagement with the cam 8 to thereby effect a relatively short stroke of the builder arm 6. Upon the rearward movement of the bar 11^a the roller 12 will be disengaged from said cam 8, leaving the arm 6 to be operated by the cam 7 in the ordinary manner.

Another bracket 13 is adjustably secured to the builder arm by a bolt 14 and is provided with a box 15 in which is journaled a 55 shaft 16, also journaled in the bracket 9.

This shaft extends longitudinally of the builder arm and is provided with a pinion 17 in mesh with a rack 18 formed on the bar 11^a. The shaft 16 is also provided with a handle 18, by which it may be manually 60 turned if desired. The shaft 16 furthermore has fixed thereto two reversely arranged ratchet wheels 19 and 20, the ratchet wheel 19 having a mutilated flattened portion 21. This ratchet wheel also carries a hub 22 provided with an annular flange 23. A coiled spring 24, secured to the hub 22, is adapted to wrap thereupon and may be attached as illustrated at 24^a to the floor on which the machine is placed. 70

A base 25, also fixed to the floor, has an upstanding socket piece 26 in which is mounted a vertically adjustable standard 27, and this standard is provided with a pawl 28 that operates on the ratchet wheel 19. 75 Another socket member 29, carried by the base 25, contains a vertically adjustable standard 30 carrying a reversely arranged pawl 31 located at a lower level than the pawl 28 and adapted to engage with the 80 ratchet wheel 20 when the arm is depressed beyond its ordinary working limits.

With this construction, if the shaft 16 is turned in one direction the bar 11^a will be moved to place the roller 12 beneath the cam 8, and therefore as said cam rotates it will be evident that a short stroke will be given to the builder arm 6. Upon each depression of the arm the pawl 28 will operate on the ratchet wheel 19, thereby turning the same 90 and the shaft 16 step-by-step, until the roller 12 is withdrawn from the cam 8. Upon its disengagement the spring 24 acts upon the shaft to move the bar 11^a to its limit, such limit being determined by a stop pin 32 that 95 abuts against the bracket 9. The cam 7 then operates on the builder arm 6 in a manner readily understood. To return the parts it is only necessary for the arm 6 to be depressed sufficiently to cause the pawl 31 to 100 engage the ratchet wheel 20, whereupon the shaft will be turned in the opposite direction and the bar 11^a moved longitudinally to cause the roller 12 to again engage beneath the cam 8. 105

From the foregoing, it is thought that the construction, operation and many advantages of the herein described invention will be apparent to those skilled in the art, without further description, and it will be under- 110

stood that various changes in the size, shape, proportion and minor details of construction may be resorted to without departing from the spirit or sacrificing any of the advantages of the invention.

Having thus fully described my invention, what I claim as new, and desire to secure by Letters Patent, is:

1. In apparatus of the character set forth, the combination with a builder arm and means for normally operating the same, of a supplemental cam, a device movably mounted on the arm and engaging the supplemental cam, a ratchet wheel on the arm 15 geared to the device, and a pawl in the path of the ratchet wheel and effecting its rotation as the builder arm moves.
2. In apparatus of the character set forth, the combination with a builder arm and means for normally operating the same, of a supplemental cam, a device movably mounted on the arm and engaging the supplemental cam, a shaft journaled on the arm and geared to the device, a ratchet wheel 25 fixed to the shaft, and a pawl in the path of the ratchet wheel and effecting its rotation as the builder arm moves.
3. In apparatus of the character set forth, the combination with a builder arm and a pair of cams for respectively operating the same, a reciprocatory rack bar on the arm having means for engagement with one of the cams, a shaft journaled on the arm and having a pinion engaged with the rack of the bar, a ratchet wheel on the shaft, and a pawl located in the path of the ratchet wheel to operate it as the arm is swung.
4. In apparatus of the character set forth, the combination with a builder arm and means for normally operating the same, of a supplemental cam, a device movably mounted on the arm and engaging the supplemental cam, means for effecting a gradual withdrawal of the device from cooperative engagement with the cam, and means for effecting a further movement of the device after its disengagement from the cam.
5. In apparatus of the character set forth, the combination with a builder arm and means for normally operating the same, of a supplemental cam, a device movably mounted on the arm and engaging the supplemental cam, means for effecting a gradual withdrawal of the device from cooperative engagement with the cam, and a spring for effecting a further and accelerated movement of the device after its disengagement from the cam.
6. In apparatus of the character set forth, the combination with a builder arm and a

pair of cams for respectively operating the same, a reciprocatory rack bar on the arm having means for engagement with one of the cams, a shaft journaled on the arm and having a pinion engaged with the rack of the bar, a ratchet wheel on the shaft, a pawl located in the path of the ratchet wheel to operate it as the arm is swung, and a spring engaged with the rack shaft to further turn the same when the device is disengaged from the cam.

7. In apparatus of the character set forth, the combination with a builder arm, of a pair of cams for respectively operating the arm, a device movably mounted on the arm and movable into and out of engagement with one of the cams, means for automatically effecting the disengaging movement of the device, and means for automatically effecting the reengagement of the device with the cam.

8. In apparatus of the character set forth, the combination with a swinging builder arm, of a pair of cams for respectively operating the arm, a device movably mounted on the arm and movable into and out of engagement with one of the cams, means for automatically effecting the disengaging movement of the device upon the normal swinging movement of the arm, and means for automatically effecting the reengagement of the device with the cam upon a greater predetermined movement of the arm.

9. In apparatus of the character set forth, the combination with a builder arm, of a pair of cams for respectively operating the arm, a device movably mounted on the arm and movable into and out of engagement with one of the cams, a shaft journaled on the arm for moving the device, and devices that automatically operate on the shaft to respectively turn it in opposite directions.

10. In apparatus of the character set forth, the combination with a builder arm, of a pair of cams for respectively operating the arm, a device movably mounted on the arm and movable into and out of engagement with one of the cams, a shaft journaled on the arm for moving the device, oppositely arranged ratchet wheels in the shaft, and pawls for respectively operating on the wheels, one of said pawls being normally disengaged from its wheel.

In testimony whereof, I affix my signature in the presence of two witnesses.

EDWARD AUSTIN WATSON.
